CLAIM

The ornamental design for a solar cell article, as shown and described.

DESCRIPTION

FIG. 1 is a front perspective view of a solar cell article in an example;

FIG. 2 is a front view thereof;

FIG. 3 is a back view thereof;

FIG. 4 is a top view thereof;

FIG. 5 is a bottom view thereof;

FIG. 6 is a first side view thereof; and

FIG. 7 is a second side view thereof.

FIG. 8 is a front perspective view of a solar cell article in an alternative example;

FIG. 9 is a front view thereof;

FIG. 10 is a back view thereof;

FIG. 11 is a top view thereof;

FIG. 12 is a bottom view thereof;

FIG. 13 is a first side view thereof; and,

FIG. 14 is a second side view thereof.

The broken lines in the figures illustrate the portions of the design that form no part of the claimed design.

1 Claim, 8 Drawing Sheets
